US00D829659S

(12) **United States Design Patent** (10) Patent No.: **US D829,659 S**
Brandt et al. (45) Date of Patent: ** Oct. 2, 2018

(54) **CONDUCTOR**

- (71) Applicant: **Eaton Corporation**, Cleveland, OH (US)
(72) Inventors: **Douglas Michael Brandt**, Wampum, PA (US); **Brad Robert Leccia**, Bethel Park, PA (US); **Richard Blaine Frye, IV**, Aliquippa, PA (US); **Zachary Ryan Jenkins**, Pittsburgh, PA (US)
(73) Assignee: **EATON INTELLIGENT POWER LIMITED**, Dublin (IE)
(**) Term: **15 Years**
(21) Appl. No.: **29/605,012**
(22) Filed: **May 23, 2017**
